STOVE DRAWER

William H. Sickinger, South Bend, Ind., assignor
to The Malleable Steel Range Manufacturing
Company, South Bend, Ind., a corporation of
Indiana

Application July 22, 1939, Serial No. 285,876

6 Claims. (Cl. 45—7.6)

This invention relates to improvements in stove drawers, and more particularly to drawers of stoves having a sheet metal exterior panel construction. This sheet metal stove construction is generally provided with concealed panel mountings, concealed door hinges, etc. Also, the panel construction extends to the doors, such as oven doors, so that said doors are of considerable thickness. The two factors of concealed hinging of doors and substantial thickness thereof generally require a certain positioning of adjacent parts to prevent interference with door pivoting. For example, in a cabinet type of stove, a drawer is generally arranged below the oven, and the oven door is hinged at its bottom. Hence, if the drawer is ajar, that is, not fully closed, or if it is not open to a substantial extent, it will interfere with the opening of the oven door.

It is therefore the primary object of this invention to provide self-acting means for fully closing a drawer, when the drawer is ajar.

A further object is to provide a drawer with an elongated guide engaged by a spring pressed pivoted member, said member bearing against the end of said guide when said drawer is open only a small extent and pressing thereagainst to fully close the drawer.

A further object is to provide a cabinet having a pivoted spring pressed door closing device, with means for holding said device in out-of-the-way, but accessible position to facilitate complete removal of the drawer.

A further object is to provide a novel drawer mounting which will guide the drawer for free movement, but will prevent tipping, sagging, and lateral play of the drawer, and which will accommodate complete removal of the drawer.

Other objects will be apparent from the description and appended claims.

In the drawing:

Fig. 1 is a fragmentary bottom plan view of a stove cabinet mounting my improved drawer.

Fig. 2 is a fragmentary vertical sectional view taken on line 2—2 of Fig. 1.

Fig. 3 is an enlarged fragmentary sectional view taken on line 3—3 of Fig. 2.

Referring to the drawing, which illustrates the preferred embodiment of my invention, the numeral 10 designates the base of a stove cabinet which mounts the frame of a stove, including frame members 11, which is enclosed by sheet metal panels 12. Frame 11 includes a horizontal frame member 13 at the front thereof and below the opening wherein drawer 14 is shiftable, said frame member 13 preferably being posi-

5 tioned forwardly from and above the front of base 10, as best illustrated in Fig. 2. The stove drawer is of any suitable construction and comprises bottom 15, side walls 16, ornamental or decorative exposed front panel 17, and back panel 18.

10 A pair of sheet metal guides extend from front to back of the stove, their front ends supported on and secured to frame member 13 and their back ends suitably secured to frame members 11. These guides are best illustrated in Fig. 3, and comprise a lower vertically positioned flange portion 19, an intermediate outwardly off-set U-shaped portion 20, and an upper vertically positioned flange portion 21 aligned with portion 19. An angle member 22 bears against and is preferably secured to flange portion 19 at the outer face thereof and extends the full height thereof to reinforce the guides and its off-set portion 20, said member 22 being suitably supported by and secured to the stove frame. A roller 23 is journaled at the rear end of each side wall 16 of the drawer and projects into channel 20 of the guide member, said roller being of a diameter only slightly less than the interior channel width, whereby the roller is free to roll in said channel, but is substantially prevented from vertical play therein. Adjacent the front of each guide member at portion 19 thereof is journaled a roller 24, said roller being positioned at the inner side of the guide which journals it. The drawer bottom 15 rests upon rollers 24. As best illustrated in Fig. 3, the parts are so arranged that the sides 16 of the drawer substantially engage the inner faces of upper flanges 21 and lower flanges 19 of the guides, to prevent lateral play of the drawer without interfering with free rolling thereof on rollers 23 and 24.

15 The drawer 14 has an elongated guide 25 extending longitudinally and centrally thereof and projecting from the bottom 15 thereof. Guide 25 has a perpendicularly bent transversely extending portion 26 at its forward end spaced rearwardly from the front of the door at a substantial distance. The rear end of guide 25 terminates in forwardly spaced relation to the rear end of the drawer. Guide 25 is of a depth less than the spacing of the bottom 15 of the drawer above frame member 13, whereby it will pass clear of said frame member when the drawer is opened. A stop 27 projects downwardly from the bottom 15 of the drawer adjacent the rear end of the drawer and is positioned to engage frame 13 to limit normal opening movement of the drawer.

A bracket 28 is fixedly mounted on the upper end of the front of base frame 10 in laterally spaced or disaligned relation to guide 25. A lever 29 is pivoted at 30 to bracket 28 and has an intermediate upwardly off-set portion 31. At the free end of lever 29 is journaled a roller 32. An elongated coil spring 33 is connected at its front to an intermediate part of lever 29, and at its rear to the rear portion of base frame 10, to normally urge said lever rearwardly. The roller 32 is positioned at the level of guide 25, and bears against end portion 26 thereof when the drawer is closed.

A bracket 34 is mounted on the front of base frame 10 between the lateral positions of bracket 28 and guide 25 of the drawer, and this bracket 34 journals an elongated rod 35 having its inner end bent perpendicularly at 36 and its outer end bent to provide a hand grip portion 37.

The drawer is freely shiftable by virtue of the rollers 23, 24 at the front and rear ends thereof, to the limit of its normal withdrawal as defined by the position of stop 27 which is so located in reference to the rollers that the latter will solidly support the drawer when fully opened. The sliding engagement of the side walls 16 of the drawer with portions 19 and 21 of the drawer guides prevents lateral play of the drawer. The close but free fit of rollers 23 in channels 20 of the drawer guides prevents the drawer from tipping when opened, even when heavily laden or pressed upon. Also, the channel-mounting of rollers 23, cooperating with the support of the bottom 15 of the drawer on rollers 24 prevents the drawer from sagging. In addition to these features of solid mounting, etc., drawer is removable from the cabinet by simply tilting the same upwardly when in normal fully open position, thereby lifting stop 27 above frame member 13 to permit free outward movement of the drawer with its rear end supported by rollers 23. I am aware that various guide constructions utilizing rollers for free drawer movement have been developed and used heretofore, but all those of which I am aware have required more than the four rollers herein provided, and have not permitted the ready and simple drawer removal provided by the above described construction and combination and arrangement of parts.

The operation of the drawer closing mechanism is as follows: When the drawer is fully closed, the parts are positioned as illustrated in full lines in Fig. 1, with roller 32 bearing against the front portion 26 of guide 25. Thence, as the drawer is opened, the lever 29 is swung forwardly by guide 25 against the action of spring 33, with roller 32 minimizing friction incident to such pivotal or swinging movement. When the drawer is opened to a given extent, say two inches or more, which will prevent its interference with the opening of oven door 40, the roller 32 will have rolled away from the guide portion 26 onto portion 25, thereby holding lever 29 against return by spring 33. However, if the drawer is opened less than said given extent and then released, the roller 32 will still be in engagement with guide portion 26, and the spring 33 will act upon the lever to swing it to normal position, thereby closing the drawer. It will thus be seen that the drawer will never stand ajar.

The retainer 35 may be swung to position with its inner end 36 engaging behind lever 29 pre-

paratory to complete removal of the drawer, to hold the lever clear of guide 25 against the action of the spring while the drawer is removed. Retainer 35 is applied and released by simply rotating it in its bracket 34.

I claim:

1. The combination with a cabinet having a drawer slidable therein, a guide extending longitudinally of said drawer and terminating in a laterally extending end portion spaced from the front of said drawer, an arm pivoted to the front of said cabinet in laterally spaced relation to said guide, a roller journaled on the free end of said arm and normally engaging the end portion of said guide, and a coil spring extending between said arm and the rear of said cabinet, said guide pivoting said arm against the action of said spring when said drawer is opened.

2. The combination with a cabinet having a drawer slidable therein, a guide extending longitudinally of said drawer and terminating in spaced relation to the front of said drawer, an arm pivoted to said cabinet in laterally spaced relation to said guide, a roller journaled on said arm and engaging said guide, and means for urging said arm rearwardly, said roller normally engaging the front end of said guide.

3. The combination with a cabinet having a drawer slidable therein, a longitudinal member carried by said drawer and terminating rearwardly of the front of the drawer, and a spring pressed arm pivoted to said cabinet in laterally spaced relation to said member, the free end of said arm normally engaging the front end of said member when said drawer is at and adjacent closed position to urge said drawer closed, shifting of said drawer to a predetermined extent from closed position pivoting said arm to inoperative position in engagement with a side of said member.

4. The combination with a cabinet having a drawer slidable therein, of a spring pressed member pivoted to said cabinet and at a concealed point spaced from the path of movement of said drawer, said member engaging a transversely extending surface of an exterior projection on said drawer, said projection pivoting said arm upon opening of said drawer, whereby said arm engages a longitudinal surface of said projection after said drawer has been opened to a predetermined extent.

5. The combination with a cabinet having a drawer slidable therein, means for urging said drawer to closed position including a spring pressed drawer-engaging arm pivoted to said cabinet and normally positioned substantially perpendicular to the direction of drawer movement and spring pressed in drawer closing direction, and means for locking said arm in fixed position relative to said cabinet and clear of said drawer.

6. The combination with a cabinet having a drawer slidable therein, a spring pressed arm pivoted to said cabinet, a longitudinal member on said drawer normally engaged by said arm, said arm pressing against the end of said member as said drawer approaches closed position and a retainer engageable with said arm to hold said arm in stationary position clear of said member, said arm normally extending transversely of said drawer.

WILLIAM H. SICKINGER.
